CLAIM

The ornamental design for a handle for a handbag, as shown and described.

DESCRIPTION

FIG. 1 is a perspective view of the handle, showing my new design;

FIG. 2 is a perspective view of the handle in another use condition;

FIG. 3 is a front view thereof;

FIG. 4 is a right view thereof;

FIG. 5 is a left view thereof;

FIG. 6 is a rear view thereof;

FIG. 7 is a top view thereof; and,

FIG. 8 is a bottom view thereof.

The broken line showing of a handbag is for illustrative purposes only and forms no part of the claimed design.
